FOREIGN PATENT DOCUMENTS

WO 9728850 A1 8/1997

Primary Examiner — Katie Jane Stofko

(74) Attorney, Agent, or Firm — Sherrill Law Offices, PLLC

(57) **CLAIM**

The ornamental design for an oral chew, as shown and described.

DESCRIPTION

FIG. 1 is a perspective view of a first embodiment of an oral chew showing my new design;

FIG. 2 is a front elevation view thereof, the rear elevation view being identical thereto;

FIG. 3 is a right side elevation view thereof, the left side elevation view being identical thereto;

FIG. 4 is a top plan view thereof;

FIG. 5 is a bottom plan view thereof;

FIG. 6 is a top plan view of a second embodiment of an oral chew showing my new design;

FIG. 7 is a front elevation view thereof; and,

FIG. 8 is a right side elevation view thereof.

The broken lines in FIGS. 1-5, 7 and 8 illustrate portions of the oral chew that form no part of the claimed design.

1 Claim, 1 Drawing Sheet(56)
